UNITED STATES PATENT OFFICE.

JAMES P. HIGH, OF FAIRVIEW, OKLAHOMA.

AIR-MOISTENING DEVICE.

1,181,886.

Specification of Letters Patent.

Patented May 2, 1916.

Application filed July 14, 1914. Serial No. 350,977.

To all whom it may concern:

Be it known that I, JAMES P. HIGH, a citizen of the United States, residing at Fairview, in the county of Major and State 5 of Oklahoma, have invented a new and useful Air-Moistening Device, of which the following is a specification.

This invention has reference to air moistening devices, and its object is to provide 10 means whereby a circulation of air in a room or other compartment is maintained, and at the same time the circulating air is humidified to a desired extent.

In accordance with the present invention 15 means are provided for producing a circulation of air, and as an electric fan is the most convenient device for such purpose, it will be considered throughout the description to follow that the circulation of air is caused 20 by an ordinary electric fan, although it will be understood that any other means for the purpose may be employed, since the invention is not confined to any specific device for causing air currents.

25 In conjunction with the fan there is provided a rotatable member responsive to the air currents to keep in motion, said rotatable member being substantially upright in operative position so as to turn upon a substantially horizontal axis, and in the path of the lower run of the rotatable member there is provided a receptacle for liquid, usually water. The arrangement is such that as the rotatable member or rotor is slowly driven 30 by air currents directed thereagainst, water gathered during the passage of the lower run of the rotatable member through the water receptacle is caused to spread over the rotor and is subjected to air currents which evaporate the water, thus correspondingly humidifying the air. The rotatable member or rotor is provided with absorbent material which does not hold the water with great tenacity, so that there is liability of 35 throwing off the water by centrifugal force.

To avoid this contingency there is provided 40 a shield or closure for the rotor, which shield may remain stationary and will arrest any water thrown off or blown from the 45 rotor, while the shield, being pervious to air currents, permits the latter to be distributed into the room or compartment and any water which may reach the walls of the shield is evaporated and added as a humidifying agent to the air.

The invention will be best understood

from a consideration of the following detailed description, taken in connection with the accompanying drawings forming part of this specification, with the further understanding that while the drawings show a practical form of the invention, the latter is not confined to any strict conformity with the showing of the drawings, but may be changed and modified, so long as such changes and modifications mark no material departure from the salient features of the invention.

In the drawings:—Figure 1 is a front elevation with some parts in section and some parts broken away of a structure embodying the present invention. Fig. 2 is a rear elevation of the device with some parts broken away and in section. Fig. 3 is a section on the line 3—3 of Fig. 1 but drawn on a larger scale and showing some parts in elevation. Fig. 4 is a plan view of the liquid receptacle of the device. Fig. 5 is a longitudinal section on a larger scale than the other figures of the hub portion of the 60 rotor and the supporting members therefor. Fig. 6 is a fragmentary cross-section of the 65 end of the tank designed to support an electric motor.

Referring to the drawings there is shown 70 a tank 1 having a top portion 2 which may constitute a permanent part of the tank, and is provided with a marginal upstanding flange 3. The top portion 2 of the tank is provided with lids 4, 5, respectively, on 75 opposite sides of an intermediately located elongated slot 6, the latter opening into a chamber 7 divided off from the interior of the tank by spaced partition walls 8, 9, respectively, these partition walls being each 80 provided with respective perforations 10, 11, whereby water placed in the tank may 85 find its way into the chamber 7. The partitions 8 and 9 not only form the chamber 7, but between these respective partitions 90 and the corresponding end walls of the tank other chambers 12, 13 are defined. The chamber 12 is readily accessible through the top 2 by means of the lid 4 and the chamber 13 is readily accessible through the top 2 95 by means of the lid 5. These lids are each provided with spaced finger holes 14 whereby the lids are readily manipulated.

Underriding the lid 5 is a support 15 provided with perforations 16, so that water 100 within the tank may find ready access thereto, wherefore the presence of the support 15

does not materially reduce the capacity of the tank 1. Both chambers 12 and 13 are designed to not only receive water, but may have ice placed therein if desirable, and in order that the tank may be drained whenever deemed necessary, a drain cock 17 is provided.

Erected on the tank 1 and preferably made fast to the partition 9 as a support therefor is a post 18 which at its upper end is provided with an entering slot 19. Carried by the post 18 is a rod 20 movable into and out of the slot 19 and held in place by a nut 21 on the corresponding end of the rod. Adjacent to the post 18 the rod has fast thereto a disk 22 which may be provided with a suitable raceway 23 for ball bearings, the balls being indicated at 24. The rod 22 overhangs the slot 6, being directed toward that end of the tank provided with the cover 4. Near that end of the rod 20 remote from the post 18 the rod is provided with another disk 25 having a raceway 26 therein for anti-friction balls 27. It will be understood that the ball bearings thus indicated may be of other types than the particular form shown, so that in this respect the invention is not confined to any special type of ball bearings.

Mounted upon the rod 20 between the disks 22 and 25 is a sleeve 28 threaded at opposite ends for the reception of threaded rings or nuts 29, 30, respectively, the ring or nut 30 having a radially expanded peripheral portion 31 designed to form a bearing for one end of a friction or brake strip 32 made fast to the post 18 by a rivet 33 or otherwise and controlled by a thumb screw 34 threaded through the post 18. By this means the sleeve 28 and parts carried thereby may be controlled as to speed of rotation for a purpose to be described.

The sleeve 28 forms the hub portion of a rotor which in the particular construction shown consists of three spiders 35, 36 and 37 each usually made of wire with an inner ring 38 and an outer ring 39, the spiders being all alike except as to diameter. The middle spider 36 is made of somewhat greater diameter than the outer spiders 35 and 37 for a purpose which will appear further on. Each spider is provided with a covering 40 of some absorbent material more or less pervious to air, of which cheese cloth or some other similar cloth may be taken as an example, and the weave of the cloth is such that the mesh is relatively open. The spiders are separated one from the other at the hub portion by washers 41, 42, respectively, the arrangement being such that the spider 35 where supported upon the sleeve 28 bears against the ring or nut 29, then comes the washer 41, then the spider 36, then the washer 42, and finally the spider 37, the latter being engaged by a ring nut 43 threaded upon an appropriate portion of the sleeve

28, so that the hub portions of all the spiders are firmly clamped together and to the sleeve 28. Beyond the nut 43 and toward the standard 18 are other washers 44, 45, respectively, engaged by the nut 30. Between the washers 44 and 45 are clamped the inner ends 46 of blades 47, each of which may be formed of a marginal loop of wire properly expanded and covered with cloth or other suitable material, and so presented to the axis of rotation as to radiate therefrom at an angle thereto, such as is usually assumed by fan blades. With such an arrangement a blast of air directed against the blades 47 tends to rotate the sleeve 28 constituting the hub of the rotor, and the spiders 35, 36 and 37 constituting the main body of the rotor.

The outer or peripheral portions 39 of the spiders are brought into contact one with the other, so that the marginal portions of the spiders constituting the rotor are of less axial thickness than the middle or hub portions, and all the spiders of the rotor have the cloth coverings of relatively coarse mesh. The diameter of the rotor is such that when carried by the post 18 the peripheral portion of the rotor enters the tank 1 through the slot 6 and dips into water which at the time may be therein.

The middle spider being of greater diameter than the outer spiders has its periphery or rim 39 radially extended beyond the corresponding rims of the other spiders, and at suitable intervals the rim 39 of the middle spider carries small cups 48 so arranged as to dip into water in the tank 1 and lift the water therefrom as the rotor revolves. More or less water is absorbed by the absorbent material during its passage through the water in the tank, and this water is carried by capillary attraction toward the hub portion of the rotor. At the same time water is elevated by the cups 48 and as they reach a high point the water gravitates therefrom, and flows over the cloth covering of the rotor, being thereby distributed toward the hub portion of the rotor.

In order to drive the rotor, and at the same time direct currents of air therethrough and into the room or compartment where it is desired to have humidified air currents, there is provided an electric fan 49 designed to be sustained by the lid 5 when upheld by the support 15. The fan 49 is to be taken as indicative of any suitable means for producing air currents, an electric fan being one of the most convenient devices for the purpose. The invention, however, is not confined to the use of an electric fan or the use of an electric fan of any particular type. Since there are many types of electric fans that are suitable for the purpose, it is not considered at all necessary to give any detailed description of the fan, and it is usually only neces-

sary to choose an electric fan having the armature on a level with the hub of the rotor of the humidifier. With the electric fan running air currents are directed against the blades 47 and these blades being at a suitable angle to the air currents tend to rotate, thus imparting rotative movements to the rotor of the humidifier, but these rotative movements may be comparatively slow, 10 so that water is lifted from the tank 1 into the path of the air currents produced by the fan 49, and these air currents passing with considerable freedom through the rotor evaporate the water carried thereby so that

15 the air currents on leaving the rotor distribute through the compartment as more or less humidified air currents. Where it is desired to lower the temperature of the air this may be accomplished by placing ice 20 in the tank 1, such ice being indicated at 49 in Figs. 3 and 6, while the water in the tank is indicated at 50 in Figs. 1, 2 and 3.

There is liability of the throwing off of water in the watery state from the rotor due 25 to strong air currents produced by the fan 49, and by centrifugal force when the rotor has sufficient speed. To avoid this there is provided a short approximately cylindrical casing 51 which has a frame 52 of wire or 30 such suitable material with radial arms 53 terminating in a ring 54 mounted on the rod 20 exterior to the ring 25, the casing being held in place by a nut 55 and washer 56 applied to the outer end of the rod 20.

35 One of the arms 53 is made fast to the partition 8, as shown at 57, and the marginal portions of the wire frame 52 are formed with foot extensions 58 made fast to the cover 2, whereby the shield is rigidly 40 supported and held against rotation.

The frame 52 has a covering 59 of suitable fabric, but preferably of finer mesh than the fabric covering the rotor, this fabric extending from the outer margins of the 45 shield to the hub portion of the rotor and also axially along the shield for its axial depth. This leaves what may be termed the rear end of the shield open, while the front end is closed with comparatively fine mesh 50 cloth. Any water which may be thrown from the rotor distributes by capillary attraction over the shield and is readily evaporated by air currents passing through the rotor and causing the rotation of the latter.

55 When the electric fan is run at relatively high speed it may impart to the rotor a higher speed of rotation than is desirable, and in such case the brake member 32 is caused to bear with appropriate force against one side face of the marginal portion 31 of the nut 30, the braking force being determined by adjustment of the screw 34.

While air currents are distributed through the room or compartment in which the humidifying device is located, and are at the

same time appropriately humidified, the air passing through the humidifier is also cleansed, since any fine particles of dust or the like which may be carried by the air are strained out or held back by the fine mesh 70 covering of the casing or shield, and by the moist surfaces of the rotor, and hence after the device has been running for a time the air in the room or compartment will be found to be markedly free from floating dust 75 and other particles.

In the foregoing description it has been assumed that the liquid placed in the tank 1 is ordinary water, but it will be understood that other liquids may be used, or the water 80 may contain materials capable of evaporation, whereby the device may be used to distribute disinfecting vapors or pleasing odors, and it is to be understood that in describing and claiming the apparatus as an 85 air moistener, the usefulness of the structure is not confined solely to the moistening of air with untreated water.

What is claimed is:—

1. An air moistener or humidifier, comprising a rotor with walls of liquid-absorbent material pervious to air currents and provided with means for causing it to rotate under the action of air currents directed through it, a water tank carrying the 95 rotor and into which said rotor dips, and a casing also on the tank and provided with walls of liquid-absorbent material pervious to air currents and located in the path of the air currents passing through the rotor, 100 portions of the walls of the casing being in peripherally surrounding relation to the rotor to receive water thrown centrifugally from the rotor.

2. An air moistener or humidifier comprising a rotor with walls of liquid-absorbent material pervious to air currents, said rotor also having a series of blades fast thereto with said blades having walls of liquid-absorbent material pervious to air 110 currents and arranged at an angle to the path of the air currents to cause rotation of the rotor, a water tank carrying the rotor and into which said rotor dips, and a casing also on the tank and provided with 115 walls of liquid-absorbent material pervious to air currents, said casing being in surrounding relation to the rotor to receive and absorb water thrown centrifugally therefrom and also having an end wall of liquid-absorbent material pervious to air currents and located in the path of air currents that have traversed the rotor.

3. An air moistener or humidifier comprising a rotor with walls of liquid-absorbent material pervious to air currents and provided with means for causing it to rotate under the action of air currents directed through it, a water tank carrying the 125 rotor and into which said rotor dips, and 130

- a casing also on the tank and provided with walls of liquid-absorbent material pervious to air currents, portions of said walls being located in the path of the air currents 5 passing through the rotor, and other portions being in surrounding relation to the rotor to catch water thrown centrifugally from the rotor, and the liquid-absorbent walls of the casing being of finer mesh than 10 those of the rotor.
4. An air moistener or humidifier comprising a rotor and a casing containing the rotor, both the casing and rotor having walls of liquid-absorbent fabric pervious to 15 air currents, and said rotor including a series of spiders spaced apart at the axial portions lengthwise of the axis of rotation and having their peripheral portions brought into close relation and there joined and constituting a skeleton support for the fabric 20 walls of the rotor, whereby the rotor is resistant to distorting forces.
5. An air moistener or humidifier comprising a tank for liquid having a top with 25 an opening therethrough, a rotor supported
- on the tank to enter the latter through the opening and dip in liquid therein, said rotor being rotatable under the action of air currents and having walls of liquid-absorbent material pervious to the air currents, 30 and a fabric casing for the rotor peripherally surrounding the latter and having one end closed by fabric, said tank being of a size to support an electric motor in position to direct air streams against the 35 rotor on the side thereof remote from the closed end of the fabric casing, and said tank being also divided interiorly into compartments for inclosing a cooling medium for liquid within the tank with said cooling 40 medium out of the path of the rotor where dipping into the tank.

In testimony, that I claim the foregoing as my own, I have hereto affixed my signature in the presence of two witnesses.

JAMES P. HIGH.
